Des. 224,856
Patented Oct. 3, 1972

224,856

CHAIR WITH SWINGABLE SEAT

Lawrence E. Charity, New York, N.Y., assignor to Sewell
& Charity Ltd., New York, N.Y.

Filed Jan. 14, 1971, Ser. No. 106,630

Term of patent 14 years

Int. Cl. D6—02

U.S. Cl. D6—49

FIG. 1 is a side view of my design for a chair with a swingable seat, the seat being shown in its normal position;

FIG. 2 is a front view of the chair;

FIG. 3 is a rear view of the chair;

FIG. 4 is a plan view of the chair;

FIG. 5 is a perspective view of the chair as seen from the rear with the seat swung down; and

FIG. 6 is a side view of the chair with the seat swung up.

I claim:

The ornamental design for a chair with swingable seat, substantially as shown.
